UNITED STATES PATENT OFFICE.

HARRY FLOYD NILES, OF CHICAGO, ILLINOIS.

BELT-LOOP.

1,099,759.

Specification of Letters Patent.

Patented June 9, 1914.

Application filed October 4, 1913. Serial No. 793,402.

To all whom it may concern:

Be it known that I, HARRY F. NILES, a citizen of the United States, and a resident of Chicago, in the county of Cook and State 5 of Illinois, have invented a new and Improved Belt-Loop, of which the following is a full, clear, and exact description.

Among the principal objects which the present invention has in view are: To reduce 10 the cost of manufacture of loops of the character specified; and to construct a loop of the character mentioned from material of light weight, to avoid bulkiness in appearance.

In the drawings, Figure 1 is a view of a 15 metal blank from which the body of the present loop is constructed; Fig. 2 is a detail view showing a mounting frame for said loop; Fig. 3 is a side view of an assembled loop and mounting frame therefor; Fig. 4 is a cross-section taken on the line 4—4 in 20 Fig. 3; Fig. 5 is a cross-section taken on the line 5—5 in Fig. 3; Fig. 6 is an assembled view showing a loop constructed and arranged in accordance with the present invention, in its assembled relation to resilient 25 garment supporters.

The present invention relates more particularly to an improvement in the belt loops described and illustrated in the patent for 30 improvements in garment supporters granted to me under date of October 1, 1912, bearing No. 1,039,995, to which patent cross reference is herein made.

The present invention is embodied in a 35 structure in which is a metal blank 11. The blank 11 is bent on the lines 12, 13 and 14, said sections extending transversely across the body of the blank 11. Adjacent the section bounded by the line 13, the blank is 40 pressed to form an upset portion bounded by the line 15 on said blank, in which the central bent portion 16 of a mounting wire 17 is placed. When said wire is so placed, the short length of the blank between the 45 line 13 and adjacent end of the blank is over-bent upon said wire to hold the same with the central bend 16 in the upset portion bounded by the line 15. The wire 17 is thus held immovably on the blank during the 50 subsequent operation of forming the loop. The second step in the operation bends the blank on the line 12, to dispose in parallel arrangement the two halves of said blank. A suitable mandrel or other form is interposed between the two halves to regulate 55 the space separating the same. The third

step in the operation of forming the loop is to bend the section of the blank extending from the line 14 to the adjacent end of the blank over the previously folded end, or 60 over the section coincident with the line 13 shown in Fig. 1 of the drawings.

The end of the blank extending from the line 14 to the adjacent extreme end is preliminarily provided with an upset shape 65 forming a ridge between lines 18 and 19, which will overlie the wire 17 and the blank enfolding the same, the fold being coincident with the line 13 in the blank, as seen in Fig. 1 of the drawings. The upset portion between the lines 18 and 19 has a bay or enlarged area indicated by the line 20 on the blank shown in Fig. 1, and seen in Fig. 3 as the bay 21. The bay 21 overlies the smaller upset portion indicated by the line 15, which 70 holds the central bend 16 of the wire 17. The lateral extensions 22 of the blank shown in Fig. 1, are now bent over an end flap 23. As seen best in Fig. 4 of the drawings, the extensions 22 hold the body section 24 and 75 the flap 23 rigidly, the body section 25 being spaced apart from the body section 24 to form a clear channel 26 to receive a belt. By so constructing the loop, it will be observed 80 that a compact and durable structure is formed without the use of solder or rivets, thereby reducing the cost of construction, 85 while increasing the durability of the article as an element of personal wear. 90

In Fig. 6 of the drawings, the loop is shown as assembled in the suspension wire coils 27, at the upper end of which coils is secured a safety-pin 28 or other suitable fastener by which the garment to be supported 95 by the belt is engaged. The assemblage of the loop, coil springs and safety-pin above-mentioned, and the means for assembling the same are fully set forth in the patent above referred to, and in said patent is also 100 described the method of employing the garment supporter of which the present loop forms an element.

Claim:

A loop as characterized, comprising a 105 sheet-metal blank having stamped offset portions adapted to overlie each other to form retaining sections, said retaining sections being adjacent the ends of said blank, said blank having lateral extensions adjacent one of said offset portions, said extensions being adapted to fold over the other end of said 110

blank when the retaining section thereon registers with the retaining section adjacent said extensions; and a mounting wire having a central bend to fit within said retaining sections, to be held therein by said lateral extensions.

In testimony whereof I have signed my

name to this specification in the presence of two subscribing witnesses.

HARRY FLOYD NILES.

Witnesses:

O. H. NICOLAI,
G. NOVAK.
